P. H. Keck,

Wash-Board,

No 11,228.

Patented July 4, 1854.

Fig. 1.

Fig. 2.

UNITED STATES PATENT OFFICE.

PHILIP H. KECK, OF MORGANTOWN, VIRGINIA.

WASHBOARD.

Specification of Letters Patent No. 11,228, dated July 4, 1854.

To all whom it may concern:

Be it known that I, PHILIP H. KECK, of Morgantown, in the county of Monongalia and State of Virginia, have invented a new and useful Improvement in Washboards; and I do hereby declare that the following is a full, clear, and exact description of the construction and operation of the same, reference being had to the annexed drawings,

10 forming part of the specification, in which—

Figure 1 is a top view of the board; and Fig. 2, a longitudinal section of the same on line $\alpha\alpha$ of Fig. 1, and perpendicular to face of board.

15 Similar letters of reference denote the same part.

The nature of my invention consists in constructing in the bottom of the washboard, a channel communicating at both extremities with the upper surface of said board, so that the rubber constructed as will be described forces the water at each stroke, through the channel and over the top of the board, for the purpose of wetting the clothes 25 and otherwise facilitating the washing operation.

To enable others skilled in the art to make and use my invention, I will proceed to describe its construction and operation.

30 In the drawing a is the board having in its upper surface the transverse grooves b common in all washboards, and in its under portion the longitudinal channel c , communicating by the openings d and e with the upper surface of the board. Above the top of the board are the covers f and g ; forming, as shown in Fig. 2, the chambers h and i . The rubber B is formed with a grooved under surface k , and sides l united by the

40 bar m , as shown in the drawing. The hinges u unite the rubber B with the slide S , the tenons p of which fit in the grooves o and confine said slide between the cheeks q of the board. This slide fits closely into the 45 chamber h , and has running through it longitudinally the channel r communicating with the opening of the vertical pipe t as seen in Fig. 2. At the lower extremity of the channel r is the valve w opening outward, the use of which will be hereafter explained.

The operation of my improved washboard is as follows: The board is placed in an ordinary tub containing sufficient water to

reach to the top of chamber h ; the board resting upon the projections y . The clothes are placed between the rubber B and grooved bottom a , and the bar m grasped by the operator, who then gives the rubber and slide a reciprocating motion with the following effect: As the slide S is drawn from the box or chamber h , the water rushes in to fill the vacuum caused by such withdrawal; and the succeeding entrance of the slide into the chamber forces the water through the opening d into the channel c and from the upper opening e over the top of the board where it falls upon the garment and completely saturates it; every downward motion of the rubber throwing up a quantity of water proportional to the capacity of the chamber h . The small valve v in the channel c which opens upward serves to prevent the water forced above it from returning. The valve w serves to exclude the water during the downward motion of the slide, and by opening to the current of air passing through the channel r and pipe t as the slide rises, facilitates the upward movement of the slide.

The tube t can be made of zinc, wood or other suitable material, and the board can be made in any of the usual modes of constructing washboards. The pressure is regulated to suit the garment operated upon, inasmuch as it is altogether performed by the hand of the operator. The advantage of this board consists in the constant flow of water upon the garment produced by the operation, and the absence of the splashing and throwing of water attendant upon the use of the ordinary washboard.

What I claim as my invention, and desire to secure by Letters Patent, is—

The construction of the washboard with the chamber h and closely fitting slide S , in combination with the channel c and openings d and e for furnishing a constant supply of water to the clothes substantially as herein fully set forth.

In testimony whereof I have hereunto signed my name before two subscribing witnesses.

P. H. KECK.

Witnesses:

HENRY SWINDLER,
K. SIEPE.
